LINER FOR MOLDS FOR LINOTYPE MACHINES

John Joseph Koblinski, Des Plaines, Ill.

Application October 23, 1939, Serial No. 300,867

1 Claim. (Cl. 199—58)

This invention relates to a liner for molds for Linotype machines and has for an object to provide a liner which can be produced cheaply.

A further object is to provide a liner which will not cause much damage if it is ejected.

A further object is to provide a liner which is constructed mostly of lead so that it will adhere more easily in the mold and will remain within the mold until it is desired to eject it.

10 A further object is to provide a liner which will be easily and quickly adjusted to the desired measure without the operator getting out of his chair.

15 A further object is to provide a liner which can be used on all standard uniform adjusted molds and can also be constructed for advertising figures and letterheads.

20 With the above and other objects in view the invention consists of certain novel details of construction and combinations of parts herein-after fully described and claimed, it being understood that various modifications may be resorted to within the scope of the appended claim without departing from the spirit or sacrificing any 25 of the advantages of the invention.

25 In the accompanying drawing forming a part of this specification:

Figure 1 is a perspective view of a liner constructed in accordance with the invention.

30 Figure 2 is a cross sectional view of the liner taken on the line 2—2 of Figure 1 looking in the direction of the arrows.

Figure 3 is a longitudinal sectional view of the liner looking in the direction of the arrows.

35 Figure 4 is a side elevation of the liner frame.

Figure 5 is an end elevation of the liner frame looking from the left of Figure 4.

Figure 6 is a side elevation of the filler.

Figure 7 is an end elevation of the filler looking from the left of Figure 6.

40 Figure 8 is a diagrammatic view of the liner showing the rib disposed at different points on the fillers.

45 Referring now to the drawing in which like characters of reference designate similar parts in the various views, the liner briefly comprises five parts, namely, a frame 10 with the center portion cut away as shown at 11 and four fillers

12 of Linotype metal, so designed as to fit into the cut away portion of the frame and with a rib 13 placed in a different position on each.

More specifically, the liner comprises a frame of substantially G-shape, formed of steel or other hard metal, the frame having the inner edges of the cut away portion beveled, as shown at 14 and 15 in Figures 2 and 3, respectively. The inner edges of the projecting portions 16 of the cut away portion of the frame are also beveled as 10 shown at 17 and 18. The beveled edges 14, 15, 17 and 18 form sloping walls for retaining the filler 12.

Each filler 12 is of the same contour as the inner cut away portion of the frame 10 and has 15 the outer edge all around its margin beveled as shown at 19 to form complementary surfaces with the sloping walls 14, 15, 17 and 18 of the frame. Each filler is provided with a rib 13, as previously described, extending from one face of 20 the filler, for engaging one of the space grooves of the molds, the rib in each filler being located in a different position from the rib of the other fillers so that by merely interchanging the fillers any desired column width may be obtained. 25

It will be noted that the liner is formed of two different metals, namely, a steel frame, and a lead filler, so that it will not cause much damage if it is ejected. Also the lead filler and rib facilitates the liner adhering easily within the 30 mold and also promotes the liner remaining in the mold until it is desired to eject it.

From the above description it is thought that the construction and operation of the invention will be fully understood without further 35 planation.

What is claimed is:

A liner for molds for Linotype machines comprising a substantially G-shaped frame of steel having the inner perimeter beveled, a filler of 40 Linotype metal of the same contour as the frame fitting into the enclosure of the frame and having its perimeter beveled to conform to the bevel of the frame, and a rib extending from one face of the filler longitudinally of the frame for engaging one of the spaced grooves of a mold. 45

JOHN JOSEPH KOBLINSKI.
